[57] CLAIM

The ornamental design for a housing for an aquarium filtration system, as shown and described.

DESCRIPTION

FIG. 1 is a front perspective view of a housing for an aquarium filtration system showing my new design;

FIG. 2 is a front elevational view thereof;

FIG. 3 is a side elevational view thereof, the opposite

side being a mirror image;

FIG. 4 is a rear elevational view thereof;

FIG. 5 is a top plan view thereof;

FIG. 6 is a bottom plan view thereof.

FIG. 1

FIG. 2

FIG. 3

FIG. 5

FIG. 4

FIG. 6
